UNITED STATES PATENT OFFICE

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY

SHOE-PRESSING MACHINE

Application filed January 14, 1928, Serial No. 246,852, and in Great Britain November 22, 1927. Renewed March 27, 1930.

This invention relates to shoe-pressing machines such as are used, for example, to apply shaping pressure to the outsoles of shoes on their lasts, this application being, in part, a continuation of my copending application Serial No. 82,029, filed on January 18, 1926.

In that copending application there is disclosed a method of shaping or leveling outsoles by different treatment at the forepart 10 and the shank respectively, the forepart being leveled by rolling pressure and the shank by pressure applied to all portions thereof substantially simultaneously. As therein explained, the use of pressure of that character 15 applied in the shank portion of the shoe by means of a suitably shaped pressing member or pad is especially advantageous in the manufacture of women's shoes of a type in which the transverse shank curvature of the 20 shoe bottom is comparatively great and in which the edges of the sole at the sides of the shank are thin and are pressed closely against the upper.

An object of the present invention is to 25 provide effective means for thus shaping the shank portion of the sole, the term "shank" being used herein to include a portion sometimes referred to as the "waist". In women's shoes there is usually a pronounced upward 30 slope of the shoe bottom at the rear of the ball-line, and in view of that condition the invention provides a novel organization including means for applying sole-shaping pressure to the shank in a direction inclined 35 forwardly toward the forepart of the shoe with respect to the direction of the height of the shoe, so that the pressure on portions of the sole immediately at the rear of the ball-line will be especially effective to impart to 40 the sole the desired transverse curvature and to press its opposite edges close to the upper. The invention is herein illustrated in its application to a type of machine shown and described in Letters Patent No. 1,549,243, 45 granted upon my application on August 11, 1925, that type of machine comprising a jack which engages the last or shoe at the heel end and forwardly of the heel end to support the shoe against upward pressure on its bottom 50 face, and a sole-pressing member or pad

which is moved upwardly to apply pressure to the bottom of the shoe. For the purposes in view, the construction herein shown comprises an organization whereby the shoe is positioned by the jack at a substantial inclination to the direction of the movement of the sole-pressing member, so that the pressure is applied to the shank portion of the sole in a direction inclined forwardly toward the forepart. As herein illustrated, the pressure is applied by means of a pad of yieldable material which is limited substantially to engagement with the shank portion of the sole and is of such contour as to accentuate the pressure on the opposite side portions of the sole.

The invention further provides a novel organization including means for supporting a shoe and last firmly against pressure applied on the bottom face of the shoe. The construction shown comprising a shoe rest shaped and arranged to serve as a firm support along the instep in a location opposite to that where the heavy conforming pressure is applied to the sole by the shank-engaging pad. As herein illustrated, the shoe rest comprises a pad which is curved in the direction of the length of the shoe to conform substantially to the curvature of the last and shoe down the instep and into the hollow so back of the toe, the shoe-engaging face of the pad being normally straight widthwise of the shoe to permit the same pad to be used interchangeably in operating on right and left shoes.

The above and other features of the invention, including also novel means for adjusting the jack for shoes of different lengths and for maintaining its parts securely in adjusted position, together with various novel details of construction and combination of parts, will now be more particularly described by reference to the accompanying drawings and pointed out in the claims.

In the drawings,

Fig. 1 is a perspective view of as much of a machine of the type illustrated in the above-mentioned Letters Patent as it is necessary to refer to for an understanding of this in-

vention, with the novel features of the invention embodied therein;

Fig. 2 is a view, partly in side elevation and partly in section, of portions of the mechanism shown in Fig. 1;

Fig. 3 is a cross-sectional view illustrating further the manner of operation of the machine on the shank portion of a shoe;

Fig. 4 is a perspective view of the instep-supporting pad and associated parts of the jack;

Fig. 5 is a perspective view of the sole-pressing pad; and

Fig. 6 shows in disassembled relation portions of the means provided for adjusting the jack and maintaining the parts in adjusted relation.

Machines of the type illustrated in the Letters Patent mentioned are twin machines, comprising duplicate mechanisms whereby one shoe is subjected to pressure simultaneously with the release from pressure of another shoe previously operated upon. Only one of such mechanisms is herein illustrated or need be referred to for an understanding of the present invention. As shown in Fig. 1, and as more fully illustrated and described in said Letters Patent, the machine is provided with a pair of vertical rods 10 on which there is adjustably secured a casting 12 which serves as a support for downwardly extending arms 14 and 16 of a shoe-supporting jack, the arm 14 having thereon at its lower end a pin 18 for engaging the heel end of the last in its spindle hole, and the arm 16, as herein illustrated, being provided for purposes of the present invention with means more particularly hereinafter described for supporting other portions of the shoe and last against the pressure applied on the sole. Mounted for vertical sliding movement on the rods 10 is a carrier 20 provided with means at its opposite sides for supporting a pair of trunnions 22 fast on a pad box 24 on which is mounted a pad 26 for applying pressure to the bottom of the shoe. The means for imparting operative movement to the carrier 20 is not shown in detail, but is fully illustrated and described in the above-mentioned Letters Patent. It will be understood that the shoe is mounted on the jack by the operator when the carrier 20 and the pad 26 are in their lowermost positions, and that in the operation of the machine the pad is moved upwardly to apply pressure to the shoe, after which the machine comes to rest, and that in the next operation of the machine the shoe is released by downward movement of the pad simultaneously with the application of pressure to a shoe by the other twin mechanism.

For purposes of this invention the last-engaging pin 18 on the arm 14 is positioned at such a height relatively to the shoe-engaging means on the arm 16 that the shoe is

presented at a substantial inclination to the direction of upward movement of the pad 26, with the forepart of the shoe upwardly inclined, so that the pressure of the pad 26 on the shank portion of the sole is applied in a direction inclined forwardly toward the forepart of the shoe, the arrangement thus being such that in operating on shoes of a style in which there is a comparatively sharp upward inclination of the sole from the ball-line toward the heel-seat the pressure is applied to portions of the sole at the rear of the ball-line in a general direction substantially perpendicular to the direction of such upward inclination of the sole. As herein illustrated, the pad 26 is so formed that it is limited substantially to engagement with the shank portion of the sole, and as indicated at 28 in Fig. 5, moreover, the pad is shaped to accentuate the pressure on the opposite side portions of the sole and thereby insure that the edges of the sole will be pressed closely against the upper. (See Fig. 3.) The pad is preferably so formed that at each end of its shank-engaging portion it presents a substantially flat face toward the sole, so that any slight engagement of the pad with portions of the sole located either forwardly or rearwardly of the shank portion will have no effect as far as altering the contour of the sole is concerned.

The pad box 24 provides a rigid support for the pad and is free to swing on the carrier 20 by means of its trunnions 22, so that the pad may adapt itself to the inclination of the shoe. The rear end of the pad, moreover, is somewhat heavier than the front end, so that the pad box and the pad will assume an inclination approximately corresponding to the inclination of the shoe even when the parts of the machine are in their idle positions. The pad is preferably formed of rubber, and may, if desired, have a covering of leather on its shoe-engaging face, as shown. At its rear end the pad is engaged and positioned by an abutment 30 which has a threaded shank 32 extending through an opening in the pad box 24 and adjustable by means of a wing nut 34 and a locking nut 36, so that the pad may be adjusted lengthwise of the shoe to position it in proper relation to the shoe. It will be understood that the pressure of the shoe on the pad tends to maintain it in engagement with the abutment 30.

For supporting the shoe against the pressure on the sole, the arm 16 of the jack is extended for a considerable distance lengthwise of the shoe and is so formed as to provide an abutment for a molded rubber pad 38 arranged to engage the top of the shoe or last continuously from the hollow at the back of the toe substantially to the rear end of the instep portion of the last, the arm and the pad having a contour lengthwise of the shoe

such as to conform substantially to the contour of the last in the location where the shoe or last is engaged by the pad. A firm support is thus provided for the last in line with the pressure applied to the shank by the pad 26 so as to insure against breaking the last under the heavy sole-shaping pressure, especially if the last is a hinge last. Preferably the front end of the pad 38 will be turned up away from the shoe, as shown, to insure against marking the shoe. The pad 38 is preferably so formed that its shoe-engaging face is straight widthwise of the shoe, so that the same pad may be used for both right and left shoes. The pad is mounted on the arm 16 between downwardly projecting flanges 40 and 42 at the opposite sides of the arm, and is so formed as to extend laterally under the edges of the flanges to avoid any possibility of contact of the metal arm 16 with the shoe. For holding the pad in position, it is so molded as to provide projections or lugs 44 on its sides which are received in openings formed in the flanges 40 and 42. The flange 42 is detachable, as illustrated particularly in Fig. 3, to permit convenient replacement of the pad when required.

The heel pin 18 is supported on a holder 46 which is pivotally mounted at 48 on the arm 14, and the holder 46 is controlled by a spring 50 which tends to tip the pin 18 in a forward direction, as common heretofore. It will be understood that when the last is mounted on the pin 18 the spring 50 by its action on the holder 46 tends to tip the shoe upwardly against the pad 38, thus assisting in maintaining the shoe in the proper position for pressure to be applied thereto by the upwardly moving pad 26.

The arms 14 and 16 of the jack are mounted for sliding movements lengthwise of the shoe along a plate 52 which is secured to the support 12. Mounted in a bearing in the support 12 is a vertical rock-shaft 54 on the lower end of which is secured a member 56 provided on its opposite sides with arms connected respectively by links 58 to the arms 14 and 16, substantially as heretofore, only one of the links 58 being shown in the drawings. By this means the arms 14 and 16 are so connected to each other as to constrain them to move either toward or from each other in unison. The machine is further provided with means for adjusting these arms toward or from each other to accommodate the jack to shoes of different lengths. For this purpose there is provided a screw 60, having right and left-hand threads thereon for engagement with corresponding threads formed in cylindrical members 62 which are swiveled in bearings formed in the arms 14 and 16 to turn about axes extending widthwise of the shoe. By turning the screw 60 the arms may thus be moved toward or from

each other. It is desirable that after the arms have thus been adjusted for any particular size of shoe, they shall be held rigidly against relative displacement in response to the pressure applied to the shoe. There is accordingly provided means for engaging the screw 60 frictionally to afford increased insurance against accidental turning movement. For this purpose each of the members 62 is provided with a threaded bore formed axially thereof, in which is mounted a small block 64 for engaging the screw 60 frictionally and also a spring 66 which presses the block against the screw and the tension of which is adjustable by means of a screw 68. It will be understood that the pressure of the blocks 64 against the screw 60 does not interfere with turning of the screw when it is required to adjust the jack, but affords substantial insurance against turning of the screw accidentally, for example in response to the pressure to which the jack is subjected in the operation of the machine on a shoe.

The manner of operation of the machine, including that of the novel features provided by the present invention, has been sufficiently described in connection with the description of the construction and requires no further explanation.

It is to be understood that while the invention is herein illustrated in its application to a machine of the type shown in the prior Letters Patent hereinbefore mentioned, in its more general aspects it is not limited to machines of that particular type; and, furthermore, that as to various novel details of construction disclosed, the invention is not limited to machines for shaping soles or for applying pressure to the shank portion of the shoe bottom exclusively.

Having described the invention, what I claim as new and desire to secure by Letters Patent of the United States is:—

1. In a machine for applying pressure to the sole of a shoe on a last, the combination of a shoe support, and means arranged relatively to said shoe support to apply pressure to the shank portion of the sole in a direction inclined forwardly with respect to the shoe to press more strongly upon the portion of the shank adjacent to the ball of the last.

2. In a machine for applying pressure to the sole of a shoe on a last, the combination of a shoe support arranged to hold the forepart of the shoe in an upwardly tilted position, a yielding pad for engaging the shank portion of the sole, and means for applying pressure to the pad so that a substantial component of pressure will be directed forwardly with respect to the shoe to press the sole more strongly at the portion of the shank adjacent to the ball of the last.

3. In a machine of the class described, a pressing member formed to apply sole-shaping pressure to the shank portion of the sole

- of a shoe, and means for supporting a shoe against the shaping pressure, said pressing member and shoe-supporting means being relatively movable in such relation as to cause said member to apply its pressure in a direction inclined forwardly toward the forepart of the shoe at such an angle to the shoe bottom as to render it effective with maximum pressure on that portion of the sole which slopes rearwardly from the ball of the shoe.
4. In a machine of the class described, a sole-pressing pad so shaped as to apply its pressure to substantially the entire shank portion of the sole of a shoe and limited substantially to engagement with the shank, and means for supporting a shoe against said pressure, said pad and the shoe-supporting means being relatively movable in such relation as to cause the pad to apply its pressure in a direction inclined forwardly toward the forepart of the shoe and substantially perpendicular to the direction of rearward inclination of the sole from the ball of the shoe.
5. In a machine of the class described, a vertically movable pressing pad formed to apply sole-shaping pressure to the shank portion of the sole of a shoe positioned bottom downward, and a jack for supporting the shoe against the pressure of the pad comprising a heel end support and another support for engaging the shoe forwardly of the heel end, said supports being constructed and arranged to position the shoe at a substantial inclination to the vertical with its forepart pointing upwardly to cause the pad to apply its pressure in a direction inclined forwardly toward the forepart of the shoe.
6. In a machine of the class described, a sole-pressing pad of yieldable material so formed as to concentrate its pressure substantially on the shank portion of the sole of a shoe and to accentuate the pressure at the opposite sides of the sole, and means for supporting the shoe against said pressure, said pad and the shoe-supporting means being relatively movable in such relation as to cause the pad to apply its pressure in a direction inclined forwardly toward the forepart of the shoe at such an angle to the shoe bottom as to render it effective with maximum pressure on that portion of the sole which slopes rearwardly from the ball of the shoe.
7. In a machine of the class described, a sole-pressing pad of yieldable material so formed as to concentrate its pressure substantially on the shank portion of the sole of a shoe, a pad box constructed to provide a rigid support for said pad, and means for supporting the shoe against the pressure of the pad, said pad box and shoe-supporting means being relatively movable in such relation as to cause the pad to apply its pressure in a direction inclined forwardly toward the forepart of the shoe.
8. In a machine of the class described, a sole-pressing pad of yieldable material formed to apply shaping pressure to the shank portion of the sole of a shoe and limited substantially to engagement with the shank, a pad box constructed to provide a rigid support for said pad, and means for supporting the shoe against the pressure of the pad.
9. In a machine of the class described, means for positioning a shoe bottom downward in an upwardly inclined position to receive pressure on its bottom face, a pad formed to apply shaping pressure to the bottom of the shoe, a support for said pad inclined similarly to the shoe, and means at the lower end of said support for adjusting the pad lengthwise of the shoe relatively to said support.
10. In a machine of the class described, means for positioning a shoe to receive pressure on its bottom face comprising members adjustable lengthwise of the shoe for shoes of different sizes, a sole-shaping pad formed to apply shaping pressure to the shank portion of the sole of a shoe and limited substantially to engagement with the shank, a support for said pad, and means for adjusting the pad lengthwise of the shoe relatively to said support.
11. In a machine of the class described, means for applying sole-shaping pressure to the shank portion of the sole of a shoe on a last in a direction inclined forwardly toward the forepart of the shoe, and means for supporting the shoe and last against said pressure comprising a member arranged to engage the instep portion of the shoe or last in line with the forwardly directed pressure applied in the shank.
12. In a machine of the class described, means for applying sole-shaping pressure to the shank portion of the sole of a shoe on a last in a direction inclined forwardly toward the forepart of the shoe, and means for supporting the shoe and last against said pressure comprising a shoe rest member arranged to engage the instep portion of the shoe or last substantially throughout the length of the instep and so shaped as to conform substantially to the lengthwise curvature of the instep.
13. In a machine of the class described, means for applying sole-shaping pressure to the shank portion of the sole of a shoe on a last in a direction inclined forwardly toward the forepart of the shoe, and means for supporting the shoe and last against said pressure comprising a shoe rest member arranged to engage the instep portion of the shoe or last, said member being so shaped as to conform substantially to the lengthwise curvature of the instep and having its work-engaging face normally straight widthwise of the shoe.

14. In a machine of the class described, a shoe-pressing pad arranged to apply sole-shaping pressure to the shank portion of the sole of a shoe on a last in a direction inclined forwardly toward the forepart of the shoe and limited substantially to engagement with the shank, and means for engaging the instep portion of the shoe or last in line with the pressure applied in the shank to support the shoe against said pressure.
15. In a machine of the class described, the combination with means for applying pressure to the bottom of a shoe on a last, of means for supporting the shoe against said pressure comprising a shoe rest pad formed to engage the instep portion of the shoe or last and to extend substantially throughout the length of the instep, said pad being shaped to conform substantially to the lengthwise curvature of the instep and having a shoe-engaging face normally straight widthwise of the shoe to permit the pad to be used interchangeably on right and left shoes.
16. In a machine of the class described, the combination with means for applying pressure to the bottom of a shoe on a last, of means for supporting the shoe against said pressure comprising a shoe rest pad formed for continuous engagement with the shoe or last substantially throughout the length of the instep and to extend forwardly into the hollow at the back of the toe, said pad being so formed at its front end as to curve outwardly away from the top of the forepart of the shoe.
17. In a machine of the class described, a shoe rest for engaging the top of a shoe forwardly of the heel end, comprising a holder provided with opposite side flanges and a molded rubber block between said flanges, said rubber block being so shaped as to extend laterally over the edges of said flanges and having projections on its sides extending into openings in said flanges to hold it in place.
18. In a machine of the class described, a shoe rest for engaging the top of a shoe forwardly of the heel end, comprising a holder provided with opposite side flanges and a molded rubber block between said flanges, said rubber block having projections on its opposite sides extending into openings in said flanges to hold it in place, and one of the flanges being detachable to permit replacement of the rubber block.
19. In a machine of the class described, the combination with means for applying pressure to the bottom of a shoe on a last, of means for supporting the shoe against said pressure comprising a heel end support and another support for engaging the shoe forwardly of the heel end, said supports being mounted for movement toward or from each other, connections between said sup-
- ports constraining them to move toward or from each other in unison, and means independent of said connections for adjusting the supports toward or from each other.
20. In a machine of the class described, the combination with means for applying pressure to the bottom of a shoe on a last, of a jack for supporting the shoe against said pressure comprising arms arranged respectively to support the shoe at the heel end and forwardly of the heel end, said arms being mounted for movements toward or from each other, connections between the outer ends of said arms constraining them to move toward or from each other in unison, and a screw connecting said arms between their opposite ends for adjusting them toward or from each other.
21. In a machine of the class described, the combination with means for applying pressure to the bottom of a shoe on a last, of a jack for supporting the shoe against said pressure comprising a heel end support and another support for engaging the shoe forwardly of the heel end, said supports being mounted for movement toward or from each other, a screw extending lengthwise of the shoe for adjusting said supports toward or from each other, and a connection between said screw and each of said supports comprising a member swivelled in each support for movement about an axis extending widthwise of the shoe and having a threaded opening to receive the screw, one at least of said members having therein means for engaging said screw frictionally to hold it from accidental turning movement.
22. In a machine of the class described, the combination with means for applying pressure to the bottom of a shoe on a last, of a jack for supporting the shoe against said pressure comprising a heel end support and another support for engaging the shoe forwardly of the heel end, said supports being mounted for movement toward or from each other, a screw extending lengthwise of the shoe for adjusting said supports toward or from each other, a connection between said screw and each of said supports comprising a cylindrical block mounted in each support to turn about an axis extending widthwise of the shoe and having a threaded opening extending through it to receive the screw, a friction member mounted in each of said blocks for engaging the side of the screw, a spring arranged to act on each friction member to press it against the screw, and means for adjusting the tension of each spring.
23. In a machine of the class described, means for supporting a shoe against pressure on its bottom face, and a pressing member formed and arranged to concentrate its pressure substantially on a portion of the bottom of the shoe at the rear of the forepart, said shoe-supporting means and pressing

member being relatively movable in such relation as to cause the pressure to be applied in a direction inclined forwardly toward the forepart of the shoe and substantially perpendicular to the direction of rearward inclination of the sole from the ball of the shoe.

24. In a machine of the class described, means for supporting a shoe bottom downward against pressure on its bottom face with the shoe as a whole so inclined as to tip its forepart upwardly, and a pressing member formed and arranged to concentrate its pressure substantially on a portion of the bottom of the shoe at the rear of the forepart, said shoe-supporting means and pressing member being relatively movable in a substantially vertical direction to cause the pressure to be applied in a direction inclined forwardly toward the forepart of the shoe.

25. In a machine of the class described, means for supporting a shoe bottom downward against pressure on its bottom face with the shoe as a whole so inclined as to tip its forepart upwardly, and a pressing member formed and arranged to concentrate its pressure substantially on a portion of the bottom of the shoe at the rear of the forepart, said pressing member being inclined similarly to the shoe and movable in a substantially vertical direction to apply its pressure in a direction inclined forwardly toward the forepart of the shoe.

26. In a machine of the class described, a sole-pressing member movable to apply shaping pressure to the sole of a shoe on a last and so formed as to concentrate its pressure substantially on a portion of the sole at the rear of the forepart, a support for said member confining it to operative movement in a fixed direction, and means for positioning the shoe at an inclination to the direction of movement of said member such as to cause the pressure to be applied in a direction inclined forwardly toward the forepart of the shoe.

27. In a machine of the class described, the combination with means for applying pressure to the bottom of a shoe on a last, of means for supporting the shoe and last against said pressure comprising a shoe rest pad of yieldable material formed to engage the instep portion of the shoe or last substantially throughout the length of the instep, said pad being shaped to conform substantially to the lengthwise curvature of the instep and having a shoe-engaging face substantially straight widthwise of the shoe when the pad is out of engagement with the shoe, and a member or arm supporting said pad and provided with a pad-engaging face similar in contour to the shoe-engaging face of the pad.

28. In a machine for applying pressure to the sole of a shoe on a last, a sole-pressing pad so formed and arranged as to concentrate its pressure substantially on a portion of the

bottom of the shoe at the rear of the forepart, and means opposite the sole-pressing face of the pad for engaging the shoe and last to cooperate with the pad in applying the pressure, said means and the pad being relatively movable in such relation as to cause the pressure to be applied in a direction inclined forwardly toward the forepart of the shoe.

In testimony whereof I have signed my name to this specification.

ERASTUS E. WINKLEY.
